CLAIM

The ornamental design for a foldable tablet computer stand, as shown and described.

DESCRIPTION

FIG. 1 is a perspective view of the foldable tablet computer stand showing my new design;

FIG. 2 is a front elevation thereof;

FIG. 3 is a rear elevation thereof; but, with the stand in folded position.

FIG. 4 is a left elevation folded view thereof;

FIG. 5 is a right elevation folded view thereof;

FIG. 6 is a bottom plan folded view thereof;

FIG. 7 is a top plan folded view thereof;

FIG. 8 is a perspective view of the tablet stand in a folded state;

FIG. 9 is a perspective view of the tablet stand in an opened state; and,

FIG. 10 is a perspective view of the stand in an alternate in use position.
